UNITED STATES PATENT OFFICE.

FRANK C. McELROY, OF COLUMBUS, OHIO.

RECORD OR ACCOUNT FILE.

SPECIFICATION forming part of Letters Patent No. 782,164, dated February 7, 1905.

Application filed June 16, 1902. Serial No. 111,807.

To all whom it may concern:

Be it known that I, FRANK C. McELROY, a citizen of the United States, residing at Columbus, in the county of Franklin and State 5 of Ohio, have invented a certain new and useful Improvement in Record or Account Files, of which the following is a specification.

My invention relates to the improvement of office-files of that class in which sheets containing accounts or records of various characters are designed to be detachably bound between two rigid cover plates or backs; and the objects of my invention are to provide an improved file and index of this character so arranged and constructed as to permit of the binding between the same back or cover plates two separated sets of bills or records which have relation to each other and to combine therewith index-sheets which shall be common to both sets of records or accounts. 20 These objects I accomplish in the manner illustrated in the accompanying drawings, in which—

Figure 1 is a view in perspective of one of my improved files, showing the same open. Fig. 2 is a rear elevation of the same, and Fig. 3 is an end view.

Similar numerals refer to similar parts throughout the several views.

In carrying out my invention I employ the usual back or cover plates 1 and 2, the rear portions of which are adjustably connected in the well-known manner by locking pins or bolts 3, there being in the present instance 35 one pair of these locking-pins arranged on each side of the center of the upper or outer back or cover plate 1. As is common in this class of files, the lower ends of the pins are secured in connection with the rear portion of 40 the lower cover-plate 2, while the upper portions of said pins pass loosely through openings in the rear portion of the upper cover-plate 1 and are adapted to be locked in connection with said upper cover-plate by a suitable locking device. (Not herein shown.) 45 Each pair of the pins 3 passes through the rear portions of the sheets, forming one set of rec-

ords, the two sets of record-sheets being indicated at 4 and 5 in the drawings. These record or account sheets 4 and 5 are arranged on opposite sides of the center of the height of the covers, with a central space, such as that indicated at 6, existing between the same. At intervals, however, I cause to be bound between corresponding leaves or sheets of both sets index-sheets 7, the latter being of such length or height as to extend across the space 6 and between the leaves or sheets of both sets. Each of these index-sheets is preferably provided with an outwardly-projecting index-letter-containing tab, such as is indicated at 8.

The advantages of the construction described will be apparent when it is understood that the sheets of one set, such as those indicated at 5, are intended for the purpose 65 of keeping thereon accounts of bills which have been paid, each sheet bearing the account of a single customer, while the sheets of the remaining set likewise contain the accounts of customers which are unpaid. When 70 one of these latter accounts is paid, the sheet containing the same is removed from its place in the unpaid account-sheets and inserted between the proper index-pages of the paid set. This system admits of the keeping of a complete 75 file for any given term of paid and unpaid accounts, which greatly facilitates the examination of either class of such accounts and admits of the ready insertion of new accounts under the proper index-heading as these accounts occur.

Having now fully described my invention, what I claim, and desire to secure by Letters Patent, is—

1. In a device of the character described, the combination with cover-plates and binding means for adjustably connecting the same, of index-sheets, and detachable subindex-leaves arranged in separated sets on opposite sides of the center of each index-sheet. 85

2. In a device of the character described, the combination with cover-plates and binding means for adjustably connecting the rear portions thereof, of separated sets of paper leaves 90

detachably held between said cover-plates, and index-sheets common to the sets arranged at intervals between the leaves of said sets and bridging the space between the sets.

- 5 3. In a device of the character described, the combination with the cover-plates and the four binding-posts, of index-sheets engaged

with all the posts and sets of opposed subindex-leaves, the leaves of each set detachably engaging two of the posts.

FRANK C. McELROY.

In presence of—
C. C. SHEPHERD,
P. S. KARSLUM.
